MARYLAND.

AIR-PIPE CONNECTION FOR ARTICULATED CARS.

Application filed June 28, 1927. Serial No. 202,104.

The invention relates to articulated cars and has particular reference to means for providing continuity of the compressed air lines throughout the sections of the car.

It is well known that the usual type of articulated car includes two or more sections mounted upon trucks and pivotally connected, other trucks being mounted beneath the pivots or points of articulation. Obviously, when a car of such construction passes over curved track the sections must move relatively at the points of articulation. It is likewise well known that in accordance with modern practice the cars are equipped with air brakes, pneumatically operated door mechanism and sanding devices. To establish continuity in the lines throughout the sections of a car, it has been ordinarily the practice to provide sections of flexible hose located beneath the pivotal connections of the sections for connecting the rigid air pipes mounted beneath the respective sections. Such flexible hose, when used in this manner, is of considerable length as it must bridge the truck located beneath or at the point of articulation of the car sections. While the car is travelling upon straight track, such an arrangement may work satisfactorily but it has been discovered that when rounding curves or making turns the hose at the inner side of the curve frequently becomes buckled or kinked resulting always in undesired wear and breaking down of the structure on account of the internal friction on the material. In some instances the kinking has been so abrupt that bursting of the hose has resulted, causing a lay-up of the car for repairs. The objections to these occurrences are readily apparent as it will be seen that a considerable financial loss is experienced owing to the high cost of maintenance and the loss of revenue while the car is being repaired.

It is with the above facts in view that we have designed the present invention which has for its general object the provision of a novel construction of connecting means which will avoid the above pointed out defects and disadvantages.

The object of the invention, more specifically stated, is to provide pipe sections stationarily mounted with respect to the truck beneath the point of articulation of car sections and having flexible connections with the rigid pipes mounted beneath the car sections

whereby a much smaller length of hose will be needed and whereby kinking thereof under any circumstances will be eliminated.

Another object of the invention is to provide an air pipe connecting structure of this character in which the relative positions of the rigid pipes carried by the car sections, the rigid pipes carried by the truck, and the flexible connecting hose sections will be such that the latter will swing or tilt laterally from the vertical rather than bend in a purely horizontal direction as in the ordinary construction, the internal friction on the material from which the hose sections are made being thereby greatly reduced so that the life thereof will be lengthened, the strain on all the parts being of course correspondingly reduced.

An additional object of the invention is to provide a connecting structure of this character which will be simple and inexpensive to manufacture, easy to install, convenient to assemble, disassemble or repair, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawing in which:

Figure 1 is a side elevation of the preferred embodiment of the invention showing it in applied position upon the center truck of an articulated car, portions of the car sections and the truck being illustrated by dot and dash lines, and

Figure 2 is a horizontal section taken on the line 2—2 of Figure 1 showing a plan of the truck and pipe members mounted thereon.

Referring more particularly to the drawing, it will be observed that we have illustrated the invention as applied to an articulated car construction of the type disclosed in our Patent No. 1,617,667 issued February 15th, 1927. The car structure itself is indicated only by dot and dash lines in the present instance inasmuch as it forms no part of the invention other than to explain the mounting and the utility of the present structure. As set forth in said patent and as shown in the drawing in the present application, the numerals 1 and 2 designate the adjacent end portions of articulated car sections

pivotedly connected at 3 above and upon a truck 4 including side frames 5 supporting a bolster 6. A bearing member of ring form indicated at 7 is mounted upon the truck and cooperates with depending bearing members 8 beneath the car sections. Bars or beam members 9 are shown as secured transversely of the member 7 and longitudinally with respect to the axis of the car sections. No claim is made to the above described mechanism and the details thereof may obviously be varied within wide limits, the elements described being mentioned only as defining an adequate foundation for the descriptive matter relating to the invention to be hereinafter set forth.

In cars of this type pipes are necessarily provided for the purpose of conducting compressed air to or from an air reservoir, control devices, door operating means, brake mechanism and sanding devices. In Figure 1 we have shown the car sections 1 and 2 as carrying pipes 10 and 11 respectively. As a matter of fact, there are generally three of such pipes on each car section though there may be more or less. It is true that Figure 1 discloses what appears to be only one in each instance, the reason being that they are all generally arranged in the same horizontal plane. This being the case the other pipes provided are located behind the two which are visible. However, the invention does not depend in any way upon the number of pipes as the principle would be exactly the same if there were only one pipe. The usual terminal treatment of such pipes need not be mentioned herein in view of the fact that in accordance with the present invention the pipes 10 and 11 preferably extend fairly close to the adjacent ends of the car section and have their ends 12 of substantially U-shape and extending in opposite directions for a reason to be explained. Clearly, it is immaterial what structure is provided for the purpose of holding the pipes 10 and 11 in place though such means may consist of the brackets indicated at 13. Whatever arrangement of valves and control devices may be employed in connection with the air system is of no consequence in this case and is therefore not dwelt upon.

Secured upon the truck 4 are pipes 14 which would of course correspond to the number of pipes 10 and 11 carried by the car sections and, as mentioned above, as there are usually three of such that number is illustrated. These pipes 14 may be mounted in any desired manner as for instance by extending them through or clamping them between bracket elements or devices 15 fastened to the truck as, for example, to the members 9, the entire purpose being to retain the metallic pipe members 14 in proper position and prevent them from becoming displaced in service. The pipes 14 are illustrated as

having their central portions outwardly offset at 16 to clear the pivotal connection 3 and not to interfere with the movements.

The pipes 14 may or may not terminate at corresponding points but it is preferable that the ends thereof be located somewhere near vertically beneath the ends of the U-shaped portions 12 of the pipes 10 and 11 for a reason which will become apparent.

For making the air lines continuous, we provide flexible hose members 17 which are connected in any suitable manner whatsoever with the ends of the U-shaped portions 12 of the pipes 10 and 11 and with the adjacent ends of the corresponding pipes 14. It will be noted that these hose members are curved outwardly in opposite directions, that is to say oppositely but longitudinally of the car so as to have sufficient length to prevent being subjected to any undue strain when pivotal movement of the car sections occurs. It will be noted that when such movement does occur the hose members 17 will not bend horizontally as in ordinary arrangements but will simply swing laterally from their normal vertical position with resultant change in curvature in accordance with variations in the distances between the ends of the pipes 10 and 11 and the ends of the pipes 14 during travel of the car upon curved track. Clearly, there will be a total absence of excessive stretching and buckling or kinking of the hose members even under the most trying circumstances or conditions. Bursting of the hose members or leakage of the joints such as might be caused by a stoppage resulting from kinking of a hose will be avoided and the excessive wear and tear on the hose members resulting from both stretching and kinking will be prevented. In view of these various facts it will be evident that the structure will remain in satisfactory operative condition for an indefinite period so that the necessity for making repairs or replacements will be rendered much less frequent than is ordinarily the case. It is believed that the construction, operation and advantages will be readily apparent to one skilled in the art without further explanation.

While we have shown and described a preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, we claim:

1. In an articulated car embodying pivotally connected sections and a truck beneath the pivot, an air system including rigid pipes car-

ried by the car sections, rigid pipes carried by the truck, and flexible connections between the first and second named pipes.

2. In an articulated car embodying pivotally connected sections and a truck beneath the pivot, an air system including rigid pipes mounted beneath the car sections, other rigid pipes mounted on top of the truck, and means flexibly connecting the first and second named pipes.

3. In an articulated car including pivotally connected car sections and a truck beneath the pivot, an air system embodying rigid pipes mounted at the bottom of the car sections, other rigid pipes carried by the truck and located in a lower plane than said first named pipes, and flexible hose members connecting the first and second named pipes.

4. In an articulated car including pivotally connected car sections and a truck beneath the pivot, an air system embodying rigid pipes mounted at the bottom of the car sections, other rigid pipes carried by the truck and located in a lower plane than said first named pipes, and flexible hose members connecting the first and second named pipes, said first named pipes terminating substantially vertically above the second named pipes.

5. In an articulated car including pivotally connected car sections and a truck beneath the pivot, an air system embodying rigid pipes mounted at the bottom of the car sections, other rigid pipes carried by the truck and located in a lower plane than said first named pipes, and flexible hose members connecting the first and second named pipes, said first named pipes having their adjacent end portions of U-shape with the terminals extending in opposite directions.

6. In an articulated car including pivotally connected car sections and a truck beneath the pivot, an air system embodying rigid pipes mounted at the bottom of the car sections, other rigid pipes carried by the truck and located in a lower plane than said first named pipes, flexible hose members connecting the first and second named pipes, said first named pipes having their adjacent end portions of U-shape with the terminals extending in opposite directions, and said flexible hose members being curved in opposite directions.

7. In an articulated car including pivotally connected car sections and a truck beneath the pivot, an air system embodying rigid pipes mounted at the bottom of the car sections, other rigid pipes carried by the truck and located in a lower plane than said first named pipes, flexible hose members connecting the first and second named pipes, said first named pipes having their adjacent end portions of U-shape with the terminals extending in opposite directions, and said flexible hose mem-

bers being curved in opposite directions and extending substantially vertically whereby to swing or tilt laterally upon pivotal movement 65 of the car sections.

8. In an articulated car embodying pivotally connected sections and a truck beneath the pivot, an air system including rigid pipes mounted beneath the car sections, other rigid 70 pipes mounted on top of the truck, and means flexibly connecting the first and second named pipes, the second named pipes having their intermediate portions laterally offset to avoid the pivotal connection of the truck with the 75 car sections.

9. In an articulated car embodying pivotally connected sections and a truck beneath the pivot, an air system including rigid pipes mounted beneath the car sections, other rigid 80 pipes mounted on top of the truck, means flexibly connecting the first and second named pipes, and means on the truck for securing the second named pipes in spaced relation.

10. In an articulated car embodying pivotally connected sections, an air system including pipes carried by the car sections, other pipes mounted at the pivot and movable relatively to both car sections, and movable connections between the first and second named 90 pipes.

11. In an articulated car embodying pivotally connected sections, an air system including rigid pipes carried by the car sections, rigid pipes mounted beneath the pivot and movable with respect to both car sections, and flexible connections between the first and second named pipes.

12. In an articulated car embodying pivotally connected sections and a truck beneath the pivot, an air system including a pipe carried by each car section, a pipe carried by the truck, and flexible connections between the first and second named pipes.

13. In an articulated car embodying pivotally connected sections and a truck beneath the pivot, an air system including pipes rigidly mounted on the car sections, other pipes rigidly mounted on the truck and located in a different plane from the first named pipes, 110 and flexible members connecting the adjacent ends of the first and second named pipes.

14. In an articulated car embodying pivotally connected sections and a truck beneath the pivot, an air system including pipes movable with the car sections, other pipes movable with the truck, and movable means connecting the first and second named pipes.

In testimony whereof we affix our signatures.
